UNITED STATES PATENT OFFICE.

SAMUEL N. KNORR, OF LAGRANGE, WYOMING.

DESIGN FOR AN ELECTRIC-LIGHTING FIXTURE.

Application filed May 21, 1928. Serial No. 26,780. Term of patent 14 years.

To all whom it may concern:

Be it known that I, SAMUEL N. KNORR, a citizen of the United States, residing at La-grange, in the county of Goshen and State of Wyoming, have invented a new, original, and ornamental Design for Electric Lighting Fix-tures, of which the following is a specification, reference being had to the accompanying drawings, forming part thereof.

Fig. 1 shows a side elevation of the fixture.

Fig. 2 shows an end view thereof.

I claim:

The ornamental design for an electric lighting fixture, as shown.

In testimony whereof I affix my signature.

SAMUEL N. KNORR.
